UNITED STATES PATENT OFFICE.

ERNEST J. SHAFFER, OF TULSA, OKLAHOMA.

SPIDER FOR SUCKER RODS AND THE LIKE.

Application filed August 28, 1926. Serial No. 132,227.

This invention has to do with a device, known as a sucker rod spider, that is intended for use in deep well, such as oil well, operations.

5 As is quite generally known, an oil well is pumped by a piston, commonly referred to as a set of cups, that is reciprocated in a working barrel at the lower end of the well tubing by means of pumping apparatus incorporated in the well rig through the intervention of a string of sucker rods.

This string is made up of rods that are screwed together, and when it becomes necessary to pull the string for the purpose of replacing worn cups, or because a rod breaks, or for any other reason, the string is lifted by means of an elevator, rod by rod, and taken apart, in a well known manner.

The device of my invention is used for 20 holding the string suspended in the tubing while the rods are being disjointed and while the elevator is being run down and connected to the next rod of the suspended string preparatory to lifting the string the length of 25 another rod. Heretofore, it has been necessary to use two elevators in this work, one to hold the string while the other elevator is being run down and applied to the next rod, and the handling of these relatively 30 heavy elevators is hard and comparatively slow work. Furthermore, when two elevators are employed, a so-called "safety hook" has to be used for transferring the hoisting line from one elevator to the other 35 and this hook is a source of danger. With my spider, only one elevator is used and it is always connected to the line, as by means of a suitable safe connection in the nature of a C-hook.

40 The objects of my invention are to provide a very simple and inexpensive device for holding the string of sucker rods suspended in the well tubing as aforesaid, and that is light and compact and convenient of use and is quick of application to, and removal from, a rod; to provide a device of the aforesaid nature that is very strong and durable and is practically immune from disorder; and to provide a device of said character that can be 45 readily changed for use with rods of different diameters.

50 Embodiments of the invention through which the foregoing objects are realized are illustrated in the accompanying drawing wherein Fig. 1 shows the device in side elevation as applied to the well tubing and as

holding a string of sucker rods; Fig. 2 is a plan view of the device as shown in Fig. 1 with the sucker rod in section; Fig. 3 is an enlarged vertical section through the device; 60 Fig. 4 is a partial plan on the same scale as Fig. 3 and showing the slips separated as for application to a rod; Figs. 5 and 6 are, respectively, a perspective view of one of the spider slips and one of the rod slips; Fig. 7 65 is a horizontal section through the spider and rod slips showing the means for connecting them together, and Figs. 8 and 9 are plan views of modifications.

The spider body is designated 1 and at 70 about its middle is shown as hexagonal in form to provide a wrench receiving portion 2. Above this portion the body is flared upwardly and outwardly, while below said portion the body is reduced in diameter and 75 threaded so that it may be screwed into the upper end of a T 3 that surmounts the well tubing 4. The string of sucker rods which operates in the tubing 4 is designated 5, and the rods of the string are connected together 80 through the usual couplings or boxes 6. The parts 3, 4 and 5 are common in oil well pumping equipment. The body 1 has a bore which, at its lower end, is cylindrical, as indicated at 10, and is of ample diameter to permit easy 85 passage of the couplings or boxes 6 of the sucker rods, and above such cylindrical portion the bore is flared upwardly and outwardly to provide what I shall term a choke 11.

Designed to fit within the choke 11 are 90 opposed spider slips 12 whose lower portions are tapered to correspond to the flare of the choke. Each spider slip is semi-circular in plan and on its inner face is provided with a semi-cylindrical recess 13 for the reception 95 of a correspondingly shaped rod holding slip 14. The recess 13 of each spider slip 12 is shouldered at its lower end to provide a substantial support for the rod slip, and the latter slip is adapted to be fastened to the 100 former slip by means of a screw 15 which passes freely through an aperture 16 in the spider slip and is threaded into a tapped hole 17 in the rod slip, the aperture 16 being counterbored to accommodate the head of the 105 screw. The pipe slips are recessed so as to form, when said slips are together, a bore designed to receive a rod of given diameter and the surface of the upper portion of said bore is formed with circumferential serrations 19 which may be either spiral or straight, while the surface of the lower por- 110

tion of such bore is formed with longitudinal teeth 19^a. The serrations 19 and teeth 19^a greatly enhance the hold of the device on the rod, the former resisting gravitation, and 5 the latter holding the string against turning during the unscrewing of the joints. By reason of the separable spider- and rod-slip construction just described, rod slips having bores of different diameters, adapting them 10 for use with different size rods, may be used interchangeably, with the same spider slips. The spider slips are attached, by screws 20, to the opposed jaws 21 of a pair of tongs 22 whose handles are designated 23. The 15 jaws 21 are normally held apart with their handles 23 outwardly by means of springs 25 which have their opposite ends contained within recesses 26 that are formed in the opposed spider slips 12 on the side thereof 20 adjacent the pivot of the tongs 22.

In the use of the device, when the string of sucker rods has been elevated to a position wherein one of the couplings or boxes 25 6 is a suitable distance above the spider body 1, the operator, holding the tongs by the handles 23, presents the slips in operative relation to the rod and brings the slips together against the tension of the springs 25 by pressing the handles 23 toward each other. As 30 soon as the slips embrace the rod the string is lowered to project the tapered lower end of the spider slips into the choke 11 of the body 1 whereupon the rod slips take a firm hold on the rod due to the choke action of 35 the device and the operator may then release his hold on the handles 23 and turn his attention to unscrewing the adjacent coupling of the string of rods and applying the elevator to the string immediately above the device. After the elevator has been connected 40 to the string, the string is lifted to the next joint and just as soon as the string starts upwardly the operator grasps the handles 23 and, holding them loosely so that they may 45 separate, permits the springs 25 to force the jaws apart thereby to release the slips from the rod. The operator then stands aside with the tongs in his hand in readiness to apply the slips to the succeeding rod as soon 50 as the next joint in the string is a proper distance above the spider body.

In the modification shown in Fig. 8, the 55 tongs are somewhat different from those of the previously described form. In the present case, the jaw and handle occurring on the same side of the longitudinal axis of the instrument are made integral so that when the handles 23^a are moved toward each other the jaws 21^a are separated. A compression spring 60 25^a is interposed between the handles 23^a and

acts to throw the handles outwardly. In this instance the operator has to press the handles toward each other for the purpose of opening the jaws and applying the instrument to the rod.

65

The action of the tongs 22^b, that are shown in Fig. 9, is similar to that of the modification just above described but in this case no spring is employed for separating the handles. Here the operator may grasp a handle in each hand and swing the handles together in presenting the instrument to the rod and separate them when he is ready to grab the rod, after which the string is lowered to project the spider slips into the 75 choke of the body 1.

70

Having thus described my invention, what I claim is:

1. A device of the character set forth comprising a body having a bore, a pair of slips for engagement within said bore, a pair of tongs comprised of members that are pivotally connected together intermediate their jaws and handles and to the jaws of which are connected the aforesaid slips, and a spring 80 interposed between the slips and located laterally of the axis of the slips toward the pivotal connection between the members of the tongs.

85

2. A device of the character set forth comprising a body having a bore, a pair of slips for engagement within said bore, a pair of tongs comprised of members that are pivotally connected together intermediate their jaws and handles and to the jaws of which are connected the aforesaid slips, the opposed slips having substantially aligned recesses located laterally of the axis of the slips toward the pivotal connection between the members of the tongs, and a compression spring having its ends confined within the recesses of the opposed slips.

90

3. A device of the character set forth comprising an integral spider body having a bore and provided with a wrench receiving portion intermediate its ends, the body flaring upwardly and outwardly above said portion and being threaded below said portion for screw connection with the upper end of well tubing, a pair of slips having tapered portions for engagement within the bore of said body whereby the slips are adapted to be forced toward each other as they enter the bore, and a pair of tongs comprised of members that are pivotally connected together intermediate their jaws and handles, said slips being secured to the jaws of the tongs.

95

In testimony whereof, I hereunto affix my signature.

ERNEST J. SHAFFER.
